UNITED STATES PATENT OFFICE.

OSCAR M. STIEGLER. OF CINCINNATI. OHIO.

DISPENSING APPARATUS.

1,163,571.

Specification of Letters Patent.

Patented Dec. 7, 1915.

Application filed July 15, 1914. Serial No. 851,198.

To all whom it may concern:

Be it known that I, OSCAR M. STIEGLER, a citizen of the United States, and resident of Cincinnati, in the county of Hamilton and State of Ohio, have invented an Improvement in Dispensing Apparatus, of which the following description, in connection with the accompanying drawing, is a specification, like characters on the drawing 10 representing like parts.

This invention relates to improvements in dispensing apparatus and is particularly adapted to sanitary devices for dispensing sugar in dining rooms, cafés and "self service" restaurants.

It is very desirable that sugar and like articles of diet be protected from germs, dust, flies, etc., and this is especially true in public dining rooms and restaurants and 20 particularly of self service restaurants in which large numbers of people, some of whom are diseased, are constantly coming and going.

It is well known that saccharine substances 25 are especially attractive to flies and that they also form a basis for the rapid propagation of various sorts of harmful germs.

One of the objects therefore of this invention is to provide an ornamental container 30 which is adapted for use upon dining room tables, counters of restaurants and particularly self service restaurants in which the contents will be protected from germs floating about in the atmosphere, from dust, 35 moisture and from the ravages of flies and other insects and to avoid the necessity of using a spoon which has been used by others.

Another object of the invention is to provide an apparatus in which a measured 40 amount of the contents may be delivered whereby only so much thereof will be furnished as the customer desires and waste avoided.

Another object of the invention is to provide means for delivering the sugar or other contents of the receptacle to a steaming cup 45 without permitting access of the steam to the interior of the receptacle whereby the sugar will be prevented from caking or from adhering to the sides of the container.

Other objects of the invention and the nature thereof will more fully appear from the following description and drawings and will be particularly pointed out in the appended claims.

In the drawings; Figure 1 is a front ele-

vation of one of the preferred forms of my invention, a portion thereof being in vertical section to show the mechanism for measuring and delivering the contents of the container. Fig. 2 is a side elevation with a portion of the container and standard broken away, Fig. 3 is a plan view, Fig. 4 is a detail vertical sectional view through the delivery chamber, and, Fig. 5 is a detail view of the lever for rotating the delivering scoops.

The preferred form of invention illustrated herein comprises a standard 1, which desirably may be circular in form and provided with recesses 2 near its base to permit the insertion of cups beneath the delivery hopper, said standard supporting a reservoir or container 3 which desirably may be of glass and provided with a removable cover 4 and may be secured to the base by an internally screw threaded and flanged annular support 5 secured to the upper portion of the base by screws 6 or other suitable fastenings.

The upper portion of the standard may be provided with two or more inclined chutes 7, 8, leading to preferably semi-circular delivery compartments 9, 10, which contain a measuring and dispensing device. The upper portion of each delivery chamber is desirably provided with a semi-circular cover 11, 12 which may be constructed of metal, glass or such other suitable material as may be found desirable. Said covers may be removably secured to the upper face of the delivery chamber casing in any suitable manner as by means of ears having suitable screws or by any other desired fastening.

The delivery mechanisms for all the compartments are desirably identical and a description of one will be sufficient. This delivery mechanism preferably comprises a series of scoops 13 mounted upon a shaft 14, which desirably may be journaled in a collared sleeve 15 set into a suitable recess 16 in the outer wall 17 of the delivery chamber 9, the collar 18 of the sleeve abutting against the inner side of the wall 17 and the sleeve being rigidly retained therein by means of a nut 19 screw threaded upon said sleeve and abutting against the outer face of the wall 17 and closing the recess 16. Rotation is imparted to the shaft 14 through a ratchet 20 which is fixedly secured upon the end of the shaft and is adapted to be engaged by a pawl 21 carried upon a lever 22 pivotally mounted upon said shaft. As illus-

trated herein the ratchet 20 is so formed that a segment 23 thereof will engage the flat face of a slabbed-off portion of the shaft 14 and the lever 22 is pivotally secured to the shaft 14 by a screw 24 secured axially of the shaft and provided with a washer 25 abutting against the side of the lever. The pawl 21 may be supported upon the lever in any suitable manner. As illustrated herein in a rectangular slideway 26 is provided and the pawl 21 supported freely therein so that its weight will cause its inclined end to rest upon the periphery of the ratchet. It will be obvious that the oscillation of the lever 22 will cause the rotation of the shaft 14 and the attached scoops 13. The scoops 13 may of course be made in any desired form, I have however found that it is desirable to make the scoops and the arms which support the same from stampings of sheet metal such as aluminum, or other metal which is not easily corroded. The entire number of scoops and the radial arms or spider which support the same may be conveniently made in two pressed out parts and the faces secured together to form the completed scoops by screws passing through the hub portion of said spider and into a flange 27 on the end of the shaft 14. The flanged end 27 of the shaft may be retained in close contact with the end of the sleeve 15 by means of a spiral spring 28 interposed between the nut 19 upon the sleeve 15 and the inner face of the ratchet 20. The scoops 13 may be of any desirable size to deliver the quantity of sugar or other material and may if desired be provided with means whereby the amount discharged may be regulated. This may be accomplished by providing means for lengthening or shortening the body of the scoop or the base thereof or by a slot having means for adjusting its width located in the back of the scoop or any other desirable means.

In order to provide for the discharging of the scoopfuls of sugar into the cup or other receptacle and to prevent the steam from rising from the cup into the dispensing apparatus the semi-circular delivery chamber 9 is desirably provided with a normally closed communicating hopper so located that the scoops in their rotation will discharge into it. The closure for the hopper which may be of any character adapted to exclude steam and moisture therefrom desirably is in the form of a gate 31 pivotally secured to the delivery chamber casing and provided with an arm 32 extending along the side of said casing and having an offset end 33 projecting into the path of the lever 22. The gate may be held normally in closed position by a spring 34 attached to the arm 32 and to a stud 35 upon the side of the casing. The spring 34 should be of sufficient strength to close the gate tightly and also to support the

lever 22 which rests upon the lateral extension 33 thereof. The amplitude of movement of the lever may be limited conveniently by studs 37, 38 projecting respectively into the path of the lever 22 and an extension 39 thereof. 70

A cap plate or cover 36 may be attached to the side of the casing of the delivery compartment to inclose the lever 22 and the mechanism to which it is attached and also 75 to prevent the access of dust and light through the slot 16. The cap plate 36 is of course slotted to permit the handle of the lever 22 to project through the same so that it may be grasped by the operator and 80 it should also be slotted to receive the arm 32.

In operation the top 4 of the container 3 is removed and the container or reservoir filled with sugar or other similar substance. It will be obvious that a sufficient quantity will 85 run through the bottom thereof and down through the chute 7 to partially fill the lower portion of the delivery chamber 9. The oscillation of the lever 22 will cause the rotation of the shaft 14 and the attached 90 scoops 13 so that they will pass through the sugar in the delivery chamber and will scoop up the amount of sugar for which they are calibrated. Upon each oscillation of the lever one scoopful of sugar will be discharged into the hopper and the final movement of the lever will cause the hopper to open and discharge the same into the cup which has been previously placed beneath the hopper. Upon releasing the lever the 100 spring 34 will raise the arm 32 immediately and close the hopper so that no material amount of steam or moisture can enter the same. 95

It is to be understood that the embodiment of the invention disclosed herein is illustrative merely and is not restrictive and that the invention may be embodied in other forms. 105

The stand, the chambers and the scoops 110 may desirably be made of silver plated metal, aluminum, white metal, or any other material which is not susceptible to corrosion and may of course be provided with any suitable ornamentation. The reservoir 115 3 may be made of any suitable material but preferably is made of cut or other ornamented glass so that the article will be attractive in appearance when placed upon the table of the dining room or restaurant. 120

Having thus described my invention, what I claim as new and desire to secure by Letters Patent is:

1. In a dispensing apparatus of the class described comprising a reservoir and a cylindrical delivery chamber having a normally closed discharge opening, a series of scoops rectangular in cross section having outer walls concentric with the axis of rotation, rotatably mounted in said delivery 130

- chamber, means for intermittently rotating said scoops through said chamber, a delivery gate and means operable at the end of each intermittent rotation of the scoop momentarily to open said gate to discharge the contents of the scoop and means for closing the gate upon the release of the lever.
2. In a dispensing apparatus of the class described comprising a reservoir and a delivery chamber having a normally closed discharge opening, a series of scoops rotatably mounted in said delivery chamber, means for intermittently rotating said scoops through said chamber comprising a ratchet and lever, a delivery gate for said chamber, means connected with said gate adapted to be engaged by said lever during its final movement to open said gate to discharge the contents of said scoop, and means for closing the gate upon release of the lever.
3. In a dispensing apparatus of the class described comprising a reservoir and a delivery chamber having a normally closed discharge opening, a series of scoops rotatably mounted in said delivery chamber, means for intermittently rotating said scoops through said chamber comprising a ratchet and lever, a delivery gate having an arm extending into the path of said lever whereby the final movement of the lever will open said gate to permit of the discharge of the contents of the scoop from the delivery chamber, a spring adapted to close the gate upon release of said lever.
4. In an apparatus of the class described comprising a reservoir, a delivery chamber communicating therewith and a rotatable series of scoops mounted in said chamber upon a substantially horizontal shaft, a bearing sleeve for said shaft mounted in a slot in the wall of the delivery chamber and removably secured therein by a collar and a nut abutting upon opposite sides of said wall and means for rotating said shaft.
5. In an apparatus of the class described comprising a reservoir, a delivery chamber communicating therewith and a rotatable series of scoops mounted in said chamber upon a substantially horizontal shaft, a bearing sleeve for said shaft mounted in a slot in the wall of the delivery chamber and removably secured therein by a collar and a nut abutting upon opposite sides of said wall and means for rotating said shaft comprising a ratchet fixedly secured upon said shaft, a lever pivotally mounted upon said shaft and provided with a pawl engaging said ratchet and means for limiting the extent of movement of said lever.
6. In an apparatus of the class described a detachable reservoir, a plurality of relatively shallow cylindrical delivery compartments communicating therewith, a rotatable series of delivery scoops removably mounted in each reservoir and means independently operable for each series of scoops adapted to rotate the same to deliver the contents of the scoop from the delivery chamber.
7. In a dispensing apparatus of the class described, a standard, a reservoir removably secured upon said standard, a plurality of oppositely disposed cylindrical delivery chambers having normally closed discharge openings, chutes connecting said reservoir with said delivery chambers, a series of measuring devices in each of said chambers, means for intermittently actuating said measuring device to cause the same to scoop up measured amounts of the contents of the chamber and to deliver the same and means operable during the final movement of each scoop adapted to open the discharge opening to deliver the material from said chamber.
8. In a dispensing apparatus of the class described, a standard, a reservoir removably secured upon the said standard, oppositely disposed chutes leading from said reservoir and terminating in semi-cylindrical receptacles, semi-cylindrical caps for said receptacles adapted to constitute in connection with said semi-cylindrical receptacles, cylindrical delivery compartments, a radial slot in the outer wall of said cylindrical delivery compartment, a sleeve detachably mounted in said slot, a shaft in said sleeve, a series of measuring devices carried by said shaft and means for rotating the shaft.
9. In a dispensing apparatus of the class described having a reservoir and a delivery chamber, a shaft mounted in the wall of said delivery chamber, a series of scoops mounted upon said shaft comprising complementary hollow pressed members secured together by suitable fastenings.
10. In an apparatus of the class described comprising a reservoir, a cylindrical delivery chamber, a horizontal shaft rotatably mounted therein, two complementary series of pressed half scoops connected by integral spiders and means for securing the hubs of said spiders together and to said shaft.
- In testimony whereof, I have signed my name to this specification, in the presence of two subscribing witnesses.
